UNITED STATES PATENT OFFICE.

MARYA KOSTUDOWICZ, OF CHICAGO, ILLINOIS.

ADJUSTABLE WINDOW-GRATING.

1,266,690.

Specification of Letters Patent. Patented May 21, 1918.

Application filed December 1, 1916. Serial No. 134,415.

To all whom it may concern:

Be it known that I, MARYA KOSTUDOWICZ, a subject of the Czar of Russia, residing at Chicago, in the county of Cook and State 5 of Illinois, have invented certain new and useful Improvements in Adjustable Window-Gratings, of which the following is a specification.

This invention relates to new and useful 10 improvements in adjustable window gratings.

The primary object of the invention is the provision of a window grating normally out 15 of the way, offering no obstruction to the window, but readily released for automatically positioning within the window frame for preventing unauthorized persons from entering the window.

A further object of the device is to provide a grating for preventing burglars from 20 entering a building through the window thereof, the device contemplating a normally depressed and inclosed protecting member, adapted for automatic movement across the 25 window frame to a predetermined regulated extent; the device being inexpensive and easily installed in connection with any window.

With these general objects in view and 30 others that will appear as the nature of the invention is better understood, the same consists in the novel combination and arrangement of parts hereinafter more fully described and illustrated in the accompanying 35 drawings and pointed out in the appended claim.

In the drawings forming a part of this application and in which like reference characters refer to corresponding parts throughout the same,

Figure 1 is an interior elevational view of a window provided with the present device showing its operative arrangement,

Fig. 2 is a vertical sectional view through 45 the same,

Fig. 3 is a view illustrating the grating in its inoperative depressed position,

Fig. 4 is a horizontal transverse sectional view taken upon line IV—IV of Fig. 3,

Fig. 5 is a horizontal transverse sectional view through the window frame of the structure shown in Fig. 3,

Fig. 6 is a perspective view of a portion of the grating employed, and

Fig. 7 is a perspective view of a portion 55 of the locking latch.

The present invention is serviceable in connection with the window of any form of building and the same is herein illustrated in connection with the side wall 10 of a 60 building having a window frame 11, arranged therein, window sashes 12 and 13 being arranged in the usual manner in the casing, which casing is provided with a window sill 14.

The house wall 10 is provided with a receiving chamber 15 for a suitable metallic grating 16, of sufficient size for moving upwardly through a slot 17 in the window sill 14, to obstruct passage through substantially 70 the entire window casing 11. The grating 16 is provided with a keeper block 18 at each of its lower corners within the chamber 15, while a helical spring 19 is arranged within the said chamber for seating the blocks 18 75 thereon.

A latch bar 20 is shiftably arranged within a side recess 21 of the wall 10 directly beneath the window sill 14, rearwardly projecting pintles 22 being arranged adjacent 80 the opposite ends of the said bar 20 surrounded by springs 23, tending to force the said bar outwardly toward the chamber 15. The springs 23 are restrained by plates 28 mounted in the inner face of the wall 10. 85 Bolts 24 outwardly projecting from the end portions of the bar 20, are adapted to enter sockets 25 in the blocks 18 when the grating 16 is at the extreme of its upper movement with the said blocks engaging the lower face 90 of the window sill 14, it being noted that a roller 26 is carried by each of the blocks 18 for engaging the adjacent inner wall of the chamber 15 during the vertical movements 95 of the said grating.

A releasing arm 27 is carried by the bar 20, slidably arranged through the wall 10 and a plate 28' secured to the said wall adjacent the window sill 14, an enlarged head 29 being carried by the said arm for inwardly moving the bar 20 against the action 100 of the springs 23. Notches 30 are arranged in the end strips 31 of the grating 16, adapted to receive the bolt 24 when the said grating is elevated at different heights, it being 105 understood that slots 32 are arranged in the side strips 31 adjacent the upper ends thereof adapted to receive the bolts 24 when the

grating is depressed within the chamber 15, with its upper end arranged within the slot 17, and a hinged door member 33 overlying the same under the influence of a suitable 5 leaf spring 34.

From this detailed description of the device, the entire operation thereof will be at once apparent, it being understood that during the day time the grating 16 is depressed within the chamber 15, as best illustrated in Fig. 3 of the drawing, and at which 10 times the springs 19 are under compression, the grating being retained by means of the bolts 24 engaging the slots 32 when desired 15 to protect the window, such as during the night time. The head 29 of the arm 27 is grasped and pulled inwardly of the wall 10, whereupon the bolts 24, being released, the grating 16 is forced upwardly by the springs 20 19 secured to bolts 24 engaged within the sockets 25 of the blocks 18 thereby locking the grating forwardly of the window opening. The opposite window strips 35 of the frame 11 are preferably provided with vertical slots 36 for receiving the side strips 31 and guiding the grating 16 during its upward movement. When the grating is elevated, the bolts 24 may be released by means 25 of the heads 29, whereupon the grating 16

may be forcibly depressed into the chamber 30 15 and locked therein, as herein described, with the door 33 automatically closing over the upper end of the grating and the slot 17. The grating 16 is designed to be formed of sufficiently strong material to prevent the 35 same from being broken, while the space between the bars of the grating as well as above the grating when the latter is elevated are of insufficient size to permit a person to enter the building therethrough. 40

What I claim as new is:—

A device of the type described, including a resiliently cushioned and incased member or guard depressible within its inclosing casing, and equipped at its lower corners 45 with blocks having sockets, a resiliently cushioned latch-bar having projecting therefrom bolts adapted to enter or engage said sockets, when the guard is elevated, said latch-bar also having means for the disengagement of its bolts from said sockets, said guard having in its end-members spaced notches also adapted to be engaged by said bolts when said guard is adjusted at different elevations. 50

In testimony whereof I affix my signature. 55

MARYA KOSTUDOWIGZ.
